ULTRA-CLEAN AIR ENVIRONMENT WORK STATION

Philip R. Austin, Livonia, Mich., assignor to Atoms-Tech Corporation, Riverton, N.J., a corporation of New Jersey

Filed Sept. 22, 1967, Ser. No. 8,686

Term of patent 14 years

(Cl. D16—2)

FIGURE 1 is a perspective view of an ultra-clean air environment work station of the present invention.

FIGURE 2 is a top plan view thereof.

FIGURE 3 is a front elevational view thereof.

FIGURE 4 is a right side elevational view thereof.

FIGURE 5 is a bottom plan view thereof.

A left side elevational view thereof would be a mirror image of the right side elevational view thereof of FIGURE 4.

I claim:

The ornamental design for an ultra-clean air environment work station, substantially as shown and described.
